UNITED STATES PATENT OFFICE.

HENRY G. PEPINO, OF NEW YORK, N. Y., ASSIGNOR TO COLGATE & CO.,
OF NEW YORK, N. Y., A FIRM.

CAKE OF SOAP.

No. 825,979.

Specification of Letters Patent.

Patented July 17, 1906.

Application filed October 6, 1904. Serial No. 227,362.

To all whom it may concern:

Be it known that I, HENRY G. PEPINO, residing in the city, county, and State of New York, have invented certain new and useful 5 Improvements in Cakes of Soap, of which the following is a specification.

My invention relates to soap for shaving purposes, and particularly to the form of the cake specifically for use in a shaving-mug. 10 Shaving-soap as such is recognized as a distinct article in the art, this being by reason of the uniform composition of the soap and absence of deleterious ingredients or elements that might tend to irritate the skin of 15 the face.

The object of the invention is to provide a cake of soap possessing the qualities mentioned, which cake will be of such form as to always be in a sanitary condition when used, 20 will not be attended with waste, will admit of the water being completely drained therefrom, and which is susceptible of being completely used up.

A further object is to insure the soap retaining its outline shape until entirely used and to provide a packing-receptacle in which the soap is sold and in which the said soap may be used, if desired.

Referring to the drawings which form part 30 of this specification, and in which similar letters of reference indicate corresponding parts, Figure 1 is a vertical sectional view of a shaving-mug and soap therein. Fig. 2 is a similar view showing the soap formed with the 35 recess corresponding in shape to the exterior form of the soap. Fig. 3 is a similar view showing the recess in the soap filled with a filling-piece of wood or other suitable material. Fig. 4 is a similar view showing a cup-shaped receptacle with the soap molded to 40 conform to the bottom of said receptacle.

It will be understood that the said cup-shaped receptacle may be used with any of the forms shown, and when put in this manner a cover is fitted on said receptacle, forming a closed package in which the soap is sold and afterward used, as shown.

Referring to the drawings, A indicates the shaving-mug, B the soap, and C the receptacle in which the soap is sold. The soap is formed with its greatest diameter at its base and its outer diameter made to conform to the diameter of the mug A at its base. The

bottom of the soap forms a joint with the bottom of the mug A or receptacle C, as the 55 case may be, and thus prevents any water from lodging under the soap in contact therewith. This receptacle I prefer to make of celluloid or other suitable material. The soap is formed in an oval shape on its sides 60 and top, so that the shaving-brush will spread over it when making the lather therefrom, and the wear of the soap has been found in practice to keep practically this form until it is almost entirely consumed. 65 To make it keep this form throughout its entire life, I employ a recess D, (shown in Fig. 2;) but this sometimes collapses before all of the soap is used, and to prevent this fault I have devised the filling-piece E. (Shown in 70 Fig. 3.) This filling-piece allows the soap to be entirely used without changing its form, and thus the brush is always spread when applied to the soap.

In Fig. 4 I show the soap in the receptacle 75 C; but the recess F is somewhat different in shape from the recess D in Fig. 2; but it may be formed in any shape desired, so long as its form is such that the soap makes a seal and its upper surface is conical, so as to spread 80 the brush when used down to this surface. The soap in this form can be completely drained when the mug is inverted, it will not become slimy, and when dry will not crack. The soap sticks to the bottom of the mug or 85 receptacle until it is entirely consumed and retains a shape which will spread the brush throughout.

It will be appreciated that a cake of shaving-soap of a shape in accordance with my 90 invention will be of circular contour at its base, at which latter it will also have its greatest diameter, the latter and said contour, however, being approximately such as to adapt said base for closely conforming 95 within the bottom of an ordinary shaving-mug. By this means not only is the cake retained in position, but the tendency of water and microbes to lodge and remain between the cake-base and interior surface of 100 the mug-bottom prevented.

When the cake is used with the receptacle C, as disclosed in Fig. 4, the central raised portion of said receptacle occupies the recess F in the under side of the soap-cake, and 105 thus constitutes a reinforce for the latter.

Having thus described my invention, what I claim as new is—

1. A cake of shaving-soap, the base of which presents the greatest of the cake-diameter, and is of circular marginal contour, said diameter and contour adapting said base for closely conforming to the bottom of an average shaving-mug, said cake upwardly diminishing in diameter from its base and having a recess in said base, for the purpose set forth.

2. A cake of shaving-soap formed with its base as its greatest diameter and circular in form, and constantly diminishing in diameter from its base to its top, and having a recess in its base approximating in form that

of the exterior of the cake, substantially as shown and described.

3. A cake of shaving-soap formed with a circular base constituting its greatest diameter, and diminishing in diameter from its base to its top, a recess in its base approximating in shape the form of the exterior of the cake, and a filling-piece fitting said recess, substantially as shown and described.

In testimony whereof I have signed my name to this specification in the presence of two subscribing witnesses.

HENRY G. PEPINO.
